(57) **CLAIM**

The ornamental design for a “fastener tab for an absorbent article,” as shown and described.

DESCRIPTION

FIG. 1 is a perspective view of a fastener tab showing my new design;

FIG. 2 is a top plan view of the fastener tab of FIG. 1;

FIG. 3 is a bottom plan view of the fastener tab of FIG. 1;

FIG. 4 is a left side elevation view of the fastener tab of FIG. 1;

FIG. 5 is a right side elevation view of the fastener tab of FIG. 1;

FIG. 6 is a front elevation view of the fastener tab of FIG. 1; and,

FIG. 7 is a rear elevation view of the fastener tab of FIG. 1. The broken lines are for illustrative purposes only and form no part of the claimed design.
